UNITED STATES PATENT OFFICE.

JOHN H. HANLON, OF SOMERVILLE, MASSACHUSETTS.

DRIFTING-VALVE.

1,378,786.

Specification of Letters Patent. Patented May 17, 1921.

Application filed October 30, 1918. Serial No. 260,222.

To all whom it may concern:

Be it known that I, JOHN H. HANLON, a citizen of the United States, residing at Somerville, county of Middlesex, State of

5 Massachusetts, have invented a certain new and useful Improvement in Drifting-Valves, of which the following is a specification, reference being had therein to the accompanying drawings.

10 My invention relates to a drifting valve for use on steam locomotives by which wet or saturated steam will be furnished to the working cylinders of the locomotive during the time when the locomotive is in motion

15 but is not being supplied with steam through the dry pipe. The use and functions of drifting valves of the type mentioned are well understood by those skilled in the art and, therefore will not be described in detail

20 here. The present invention is an improvement of the drifting valve shown in my prior application for United States Letters Patent filed Oct. 24, 1917, Serial No. 198,217 to which reference may be had. The drifting

25 valve forming the subject matter of my present invention is simpler in construction and more reliable in its operation than the valve shown in my prior application. It does, however, embody the essential features

30 of the drifting valve therein shown.

The invention will be fully understood from the following description when taken in connection with the accompanying drawings and the novel features thereof will be 35 pointed out and clearly defined in the claims at the close of this specification.

In the drawings, Figure 1 is a side elevation of a locomotive to which is applied a drifting valve embodying my invention.

40 Fig. 2 is a vertical section of the main valve and operating mechanism.

Fig. 3 is a vertical section taken on line 3—3 of Fig. 2.

45 Fig. 4 is a vertical section of the secondary valve.

Referring now to the drawings the main valve casing is indicated at 14 and the main valve at 15. The secondary valve casing is designated 16 and the valve is designated 50 17. The main valve casing is connected by a pipe 18 with the boiler. The casing is also connected by the pipes 19 and 20 with the two working cylinders of the locomotive only one cylinder being shown in the draw-

ings. The steam passage afforded by the 55 pipe 19 also leads through the secondary valve 16, said secondary valve being conveniently located on the top of the steam chest. At 21 is shown a pipe leading from the secondary valve casing 16 to the trip 60 cylinder 22. The piston 23 of the trip cylinder 22 is moved toward the left as seen in Fig. 3 by a spring 24 surrounding a rod 25 and is moved in the other direction by a steam pressure within the trip cylinder 22. 65

The main valve 15 is provided with an auxiliary valve 171 which opens first and by admitting steam to the space 38 beneath the piston-shaped lower end 39 of the main valve 15 equalizes the pressure on both sides 70 of the main valve so that the main valve may be lifted with less effort. The main valve is lifted by a plunger 26, the stem of which extends through a stuffing box 27 and into the path of a cam 28 having a tail 75 g which is acted upon by the throttle lever 29 through the interposition of a swinging dog 30 pivoted at 31 to the bracket 32 which supports the mechanism.

The tension on the spring 24 is adjusted 80 by means of the thimble 33 and check nut 34.

The secondary valve which is placed on the top of the locomotive cylinder has a movable valve member 17 which is normally open. In the drawings, I have shown the 85 valve as placed vertically so that the valve is held open by the action of gravity but other means may be provided if the valve is in a different location. This valve member 17 engages a valve seat α and closes the passage leading from the main valve to the locomotive cylinders. The pipe 21 which leads to the trip cylinder connects with a port 35 which intercepts the valve seat α and therefore is closed whenever the secondary valve 90 is on its seat. At 36 is shown a bleeder port by which the steam between the main valve and the secondary valve may escape to the atmosphere and at 37 is shown another bleeder port by which the steam in the trip 95 cylinder and the pipe leading to it may escape to the atmosphere. This port is of an area much smaller than that of port 35 so that the escape of steam through port 37 will not prevent the accumulation of pressure in the trip cylinder as long as valve 17 is open.

My improved drifting valve operates in

the following manner: As long as the locomotive is running with open throttle, the main valve 15 and the secondary valve 16 remain closed, due to the pressure on the 5 upper side of the main valve 15 and on the lower side of the secondary valve member 17 respectively. Since these valves are closed, no steam can reach the trip cylinder 22. When the engineer shuts off the throttle on 10 beginning to go down grade, the throttle moves the dog 30 which in turn moves the tail 9 of the cam 28 opening the main valve 14. When the main valve 14 is opened, steam passes through the pipe 19 and secondary valve 16 to the locomotive cylinder. As long as the locomotive is running the 15 suction in the locomotive will cause the steam to flow freely into the locomotive cylinders and no back pressure will be built up. The trip cylinder will, therefore, remain in the position shown in Fig. 3 as long as the locomotive continues to move. As soon as the locomotive ceases moving, pressure will be built up and steam will enter 20 the trip cylinder through the port 35 and pipe 21. The trip cylinder is designed in size to be sensitive to a pressure less than that which is likely to cause the locomotive to move. In practice I design it so that 25 the trip cylinder will move when the pressure reaches about fifteen pounds to the square inch. When this pressure is attained the piston moves to the right out from under the plunger 26 and the main valve 14 closes 30 shutting off the supply of steam to the locomotive cylinders. The bleeder port 36 then reduces the pressure in the pipe 19. At the same time the steam in the trip cylinder escapes through the bleeder port 37. As 35 soon as the pressure in the trip cylinder 22 has been reduced sufficiently the spring 24 pushes back the piston 23 and replaces the cam 28 under the end of the plunger 26 resetting the device. When steam is next admitted to the working cylinders of the locomotive the increase in pressure immediately 40 seats the valve 17 so that there can be no leakage from the cylinders at this point.

What I claim is:

50 1. In a device of the character described, a main valve controlling a steam passage leading from the boiler to the cylinders of the locomotive, throttle actuated mechanism to open said main valve by the movement 55 which closes the throttle, a trip cylinder operatively connected with said main valve and connections to the trip cylinder entering said steam passage at a point near the cylinders of the locomotive whereby an accumulation 60 of pressure in the cylinders of the locomotive will produce pressure in the trip cylinder and actuate the trip cylinder to permit the closing of the said main valve.

65 2. In a device of the character described, a main valve controlling a steam passage

leading from the boiler to the cylinders of the locomotive, throttle actuated mechanism to open said main valve by the movement which closes the throttle, a trip cylinder operatively connected with said main valve, 70 connections to the trip cylinder entering said steam passage at a point near the cylinders of the locomotive, and a valve in said steam passage operated by accumulation of pressure in the locomotive cylinders to close said 75 steam passage whenever the throttle is open.

3. In a device of the character described, a main valve, a casing therefor, connections from the boiler to the casing, connections from the casing to a locomotive cylinder, a 80 trip cylinder operatively connected with said main valve, a valve and valve casing in the connection leading to the locomotive cylinder, and a connection from said last mentioned valve casing to said trip cylinder both 85 the steam passage between the main valve and the cylinders and the connection between the trip cylinder and said second mentioned casing being controlled by the valve therein. 90

4. In a device of the character described, a main valve and casing therefor, a secondary valve and casing therefor, a trip cylinder operatively connected with said main valve, steam connections connecting the 95 boiler with the main valve casing, the main valve casing with the locomotive cylinders through the secondary valve casing, and the secondary valve casing with the trip cylinder, and throttle operated means for opening the main valve by the closing movement of the throttle, said main valve being released by the trip cylinder and thereby permitted to close upon accumulation of pressure in the trip cylinder. 100

5. In a device of the character described, a main valve and casing therefor, a secondary valve and casing therefor, a trip cylinder operatively connected with said main valve and releasing said main valve and permitting it to close upon accumulation of pressure in said trip cylinder, steam connections connecting the boiler with the main valve casing, the main valve casing with the locomotive cylinders through the secondary valve casing, and the secondary valve casing with the trip cylinder, said steam connection to the trip cylinder entering the steam connection from the main valve to the locomotive cylinder through the valve seat 110 of the secondary valve so that the said valve member controls both steam passages. 115

6. In a device of the character described, a main valve and casing therefor, a secondary valve and casing therefor, a trip cylinder operatively connected with said main valve and releasing said main valve and permitting it to close upon accumulation of pressure in said trip cylinder, steam connections connecting the boiler with the main valve cas- 125 130

ing, the main valve casing with the locomotive cylinders through the secondary valve casing, and the secondary valve casing with the trip cylinder, said steam connection to the trip cylinder entering the steam connection from the main valve to the locomotive cylinder through the valve seat of the secondary valve so that the said valve member controls both steam passages, there being a bleeder port connecting the trip cylinder passages with the atmosphere.

In testimony whereof I affix my signature.

JOHN H. HANLON.
